UNITED STATES PATENT OFFICE.

EDWARD JACKSON, OF READING, PENNSYLVANIA, ASSIGNOR TO THE NOLDE AND HORST COMPANY, OF READING, PENNSYLVANIA, A CORPORATION OF PENNSYLVANIA.

TUCKING MECHANISM FOR CIRCULAR-KNITTING MACHINES.

Application filed December 20, 1923. Serial No. 681,707.

My invention relates to circular knitting machines and particularly to those adapted for "tuck stitch" work and employing determined long latch needles with intermittently actuated latch-clearing cam-mechanism therefor; my object being to provide for the automatic selection and control of the tucking or non-tucking action of different ones of said long-latch needles, as governed by a pattern mechanism for the production of lace work or clock stripes in circularly knit stockings. My improvements are fully described in connection with the accompanying drawings, and the novel features are particularly set forth in the subjoined claims.

Fig. 1 indicates in side elevation portions of a usual circular knitting machine having my improvements applied thereto.

Fig. 2 is a view corresponding with Fig. 1 but taken at right angles thereto.

Fig. 3 is an enlarged partial plan view of the knitting head, showing my improved automatic control mechanism for the latch clearing cams.

Fig. 4 is a diagrammatic view showing the knitting cams.

Fig. 5 is a diagrammatic showing of an arrangement of the differently butted circle of needles for producing lace clocks, the heavy lines indicating long latch needles spaced among the regular length latch needles.

Figs. 6 and 7 indicate respectively the short butt and long butt regular length latch needles; and Figs. 8 and 9 indicate the differently butted longer latch needles employed.

Fig. 10 indicates a pattern disc controlling the selection of long-latch needles; and Fig. 11 shows a cam for controlling the tucking or non-tucking action of the needles in successive courses.

Fig. 12 is a detail view of a special pattern actuated locking latch device.

Fig. 13 is a diagrammatic view of a portion of a stocking indicating a clocking pattern producible with my improved mechanism.

The drawings show my improvements applied to the well known "Banner" type of machine more fully set forth in Hemphill

Patent No. 933,443 of Sept. 7, 1909, though the improvements are equally applicable to other known circular knitting machines.

In the drawings A represents the frame of the machine, B the fixed cam cylinder, C the knitting cam head, D the rotated needle cylinder, and E the pattern drum shaft actuated by pattern chain F. These operate in usual known manner for the production of circular knit stockings.

To produce tuck stitches, special long-latch needles are employed as heretofore, spaced among the regular-length latch needles; and to control their tucking or non-tucking movements special tucking cams are employed, one cam 10 shown being an extension of stitch cam 6 for clearing the longer latches and actuated through its projecting shank portion 11 in the manner more fully set forth in Robinson Patent No. 1,425,288, of August 8, 1922. The action of cam 10 in the present invention is determined by special pattern-controlled mechanism adapted to affect the movements of said cam so as to produce tuck and non-tuck stitches in selective successive courses, and also to selectively act in each course on determined ones only of said differently butted long-latch needles.

The long-latch needles may be variously disposed among the regular-length latch needles, and in Fig. 5 I have diagrammatically indicated one arrangement for producing a lace-clock stripe on each side of a stocking; the radial lines indicating the different butt lengths of their respective needles, the light and heavy lines representing respectively regular length and long-latch needles. In the arrangement shown, the circular series of needles is divided into the usual half-circle series of long-butt needles 20, and short butt needles 30 employed in knitting stockings; and for producing the lace-clock stripes indicated, alternate ones of the long-butt needles 20, adjacent the diametral opposite ends of their series, are replaced with long-latch needles. These substituted long-latch needles, ten as shown, are arranged in groups of different butt-lengths, the central pair 21, 21 having intermediate-length butts, that is butts shorter than the series of long-butt needles 20, but

longer than the series of short-butt needles 30; the pairs 22, 22 and 22, 22 flanking said central pair, having long-butts corresponding in length with the butts of the series 20; 5 and the end pair 23, 23 and 23, 23 having extra long butts that is longer than the butts of said series 20; preferably leaving as shown, a regular-length latch long-butt needle 20 at each end of the half-circle series of 10 the latter. Tucking action on these long-latch needles is effected as usual by clearing their latches only every two or three courses through the extra lift effected by cam 10 as set out in Robinson patent aforesaid.

15 My improved mechanism provides for tucking action on selected long-latch needles by determinedly limiting the extent of withdrawal movement of said cam 10 from the path of the needle butts in certain 20 courses, producing tuck stitches on certain needles, as: On said central pair 21, 21 only; or on the latter and flanking pairs 22, 22 and 22, 22; or on all said long-latch needles. By 25 variously arranging said groupings or different groupings of long-latch needles, other effects may be readily produced.

Cam 10 is actuated as heretofore through its shank portion 11 and is normally projected into the path of the needle butts by 30 spring 14, and positively withdrawn out of said path when tucking stitches are desired, as set forth in said Robinson patent. In the present construction lever 40 is employed to limit said cam movement, said lever being 35 intermediately pivoted at 41, and engaging a stud 42 on shank 11, its opposite end 43 having imparted to it determined pattern controlled movements to position cam 10 more or less out of the path of the needle 40 butts so as to miss one, two, three, or all the groups of long-latch needles 21, 22 and 23.

This pattern mechanism, as shown in the drawings, comprises a pattern disc 50, carried on pattern drum shaft E; an intermediately pivoted lever 51, having an end riding on the stepped circumference of said disc 50 under tension of spring 52, and its other end connected by a rod 53 to one end of a bell-crank 54. A cam-shifting rod 55 50 is connected to the other end of said bell-crank and has its free end loosely projected through the apertured end 43 of lever 40; said rod carrying an adjustable stop 56 and compressible spring 57, to respectively engage the opposite faces of said apertured lever end 43, so as to position lever 40 and variably limit the withdrawal movement of cam 10 from the path of the needle butts. Spring 57 normally holds lever end 43 60 against stop 56 but yields to permit independent movement of lever 40, as later herein described; and tension of spring 52 being greater than tension of spring 57 permits such independent movement without disturbing 65 the adjusted position of rod 55 and its

stop 56. Pattern disc 50 is stepped as shown to variously shift lever 40 and its connected mechanism, and is rotated with the usual pattern drum so as to control the tucking action at the proper time in the knitting of a 70 stocking.

To clear the long latches of their accumulated loops every few courses, the latch-clearing cam 10 must be projected fully into the needle path; and this is accomplished, 75 as shown in the drawings by a special disc cam 60, mounted in a bracket 61 and constantly rotated in one direction by a pawl 62, eccentrically carried by the main shaft 63, and actuating ratchet wheels 64, a detent 80 65 preventing reverse movement of said disc. Bearing against the cam edge of disc 60 under tension of spring 66, is a push rod 67 carried by bracket 68; and said rod, under action of disc 60, swings lever 40 on its pivot 85 41 to free tucking-cam shank 11 to the entering action of spring 14 as heretofore. This swinging movement of lever 40 as before described merely compresses spring 57 without disturbing the adjusted position of 90 stop 56 against which latter lever end 43 seats when disc 60 permits push rod 67 to withdraw from contact with lever 40.

From the foregoing description it will be seen that the shape of pattern disc 50 will 95 determine the extent of possible movement of tucking cam 10 from none to maximum, while cam disc 60 will cause determined intermittent movement of the latter when required to clear the longer latches and the 100 spaced arrangement of the differently butted long-latch needles will determine the pattern effects possible by the combined action of said discs 50 and 60.

To permit of other tucking stitch effects, 105 independent of those controlled by cam 10, as for instance imitation narrowing marks in the rear half of the stocking leg, I provide, as shown in the drawings, extra-short-butt long-latch needles 80, 80 spaced among 110 the regular-latch short-butt needles 30. And to cause such needles 80, 80 to tuck when desired, the top center cam 5 is made slidably retractable from the needle cylinder sufficiently to miss said butts 80, 80 and cause 115 them to pass above stitch cam 7 instead of below the latter, thus retaining the thread loops on their needles until cleared by return movement of cam 5, when they will resume regular knitting travel. This retraction of cam 5 must be timed with the movement of cam 10, taking place when the latter is fully projected into needle-butt path so that the butts of needles 80, 80 will be raised sufficiently to pass over top of cam 7. 120 Retractive action of cam 5 is automatically controlled, as shown, by a second pattern disc 105 on pattern shaft E, and a second cam disc 90 carried by bracket 61. Disc 90, as shown, is formed integrally with disc 60 125

and actuates a push rod 91 carried in bracket 68. A spring 92 holds said rod in contact against said pattern disc, and the forward end is provided with a fixed arm 93 and a 5 resilient arm 94 engaging a stud 5^a on cam 5 to respectively withdraw the latter partly from the path of the needle butts and tension the same for return at the proper time, in a manner similar to the action of cam 10.

10 As cam 90 constantly rotates, rod 91 is provided with a detent 95 for engagement by a locking latch member 96 to hold said rod in extended idle position, to retain cam 5 normally fully projected for regular knitting action.

15 Latch member 96 is pivoted at 97 to the frame and is operated by a lever 98 pivoted at 99, the free end of the latter being connected by a rod 100 to a pattern-actuated lever 101 similar to lever 51 and 20 carried on the pivot stud of the latter. The free end of lever 101 is held by a spring, similar to spring 55, in contact with the cam face of pattern disc 105 and actuated at proper times by the latter to free push rod 25 to the action of disc 90. It will be understood that cam 5 is not limited to action on needle butts intended solely for imitation narrowing marks in a stocking but may be combined with cam 10 and differently located extra short butt long-latch needles in 30 the production of tuck stitch designs.

My improvements thus fully described provide in a simple and effective manner for the automatic production of a great variety 35 of tuck stitch effects, and the mechanism specifically set forth may obviously be modified in detail without departing from my invention. For instance additional pattern ef-

fects may be secured by employing a cam 110 to reraise certain of the long-latch needles to pass above cam 7 so as to effect tucking action only on the long-butts while regular knitting is effected on the shorter butts, such cam 110 being movable into and out of the path of said needle butts and controlled by hand or mechanism similar to pattern discs 50 and 60. Other modifications and arrangements may be readily devised.

What I claim is:

1. In a circular knitting machine, a circular series of needles comprising a number all of which have lengthened latches but certain of which have butts of different length from others, an intermittently operated radially movable latch-clearing cam for said lengthened-latch needles, and means for limiting said radial movement comprising a movable pattern-controlled rod for said cam, and fixed and yielding stops on said rod adapted respectively to limit the movement 60 of said cam in one direction and permit intermittent movement in a reverse direction.

2. In a circular knitting machine, a circular series of needles comprising a number all of which have lengthened latches but certain of which have butts of different length from others, a radially rovable latch-clearing cam for said lengthened-latch needles, a movable member controlling the radial movement of said cam, pattern-drum controlled 70 mechanism for limiting movement of said member in one direction, and a separate pattern disc for effecting at times reverse movement of said member.

In testimony whereof I affix my signature.
EDWARD JACKSON.
